[57] **CLAIM**

An ornamental design for a cam latch extrusion for a trailer door, as shown and described.

DESCRIPTION

FIG. 1 is a perspective view of a cam latch extrusion for a trailer door illustrating my new design;

FIG. 2 is a perspective view of the cam latch extrusion for a trailer door illustrated in FIG. 1 shown installed on the rear door of a trailer for transporting horses or other livestock; the broken lines are for environmental purposes only and form no part of the claimed design;

FIG. 3 is an enlarged end view of the cam latch extrusion for a trailer door shown in FIGS. 1 and 2, taken substantially from the circumscribed portion of FIG. 2, the opposite end view being the mirror image of that shown; and,

FIG. 4 is an enlarged front view of the cam latch extrusion for a trailer door shown in FIGS. 1 and 3.
